UNITED STATES PATENT OFFICE.

CHARLES F. HALL, OF SKANEATELES, NEW YORK.

IMPROVEMENT IN MACHINES FOR REFITTING GLOBE-VALVES.

Specification forming part of Letters Patent No. 172,624, dated January 25, 1876; application filed February 16, 1875.

CASE B.

To all whom it may concern:

Be it known that I, CHARLES F. HALL, of Skaneateles, in the county of Onondaga and State of New York, have invented a new and Improved Machine for Refitting Globe-Valves, Stop-Cocks, &c., of which the following is a specification:

The invention will first be described in connection with drawing, and then pointed out in the claims.

Figure 1 is a longitudinal sectional elevation of the apparatus for refitting the valves and the plugs for the cocks. Fig. 2 represents the same, partly in side elevation and partly in sectional elevation, showing a modification of some of the details. Fig. 3 is a transverse section, taken on the line $x-x$ of Fig. 1. Fig. 4 is a transverse section taken on the line $y-y$ of Fig. 1. Fig. 5 is a section on the line $z-z$ of Fig. 4, and Fig. 6 represents different forms or arrangements of cutters that I propose to use.

Similar letters of reference indicate corresponding parts.

The plugs A, for stop-cocks, such as represented in dotted lines in Fig. 1, also the valves of the ordinary globe-valves, are to be suspended upon the centers B and C, to be acted on by cutters D E, &c., the said valves or plugs being turned against the cutters, which are held stationary, the turning being effected by a wrench or handle applied to center C, and the latter having a dog or carrier, F, adapted for holding the plugs or valves.

The center C turns freely in an adjusting-screw, G, which screws in the stand H to set the center up to the plug or valve, and is held in position by a jam-nut, I, on it, screwing against the stand H.

The center B is mounted in a hollow spindle or shaft, J, supported in a stand, K, and made adjustable in its lengthwise direction to shift the apparatus for holding short or long plugs or valves; but it is prevented from turning by a binding-screw, L.

The said center B may either pass through shaft J its whole length, as represented in Fig. 1, screwing in it a part of the way for adjusting it endwise, or it may extend part of

the way through, as represented in Fig. 2, with a spiral spring, M, and an adjusting-screw, J, behind, for pressing it against the valve or plug with an elastic action.

The cutters D E, &c., which are of different forms, to correspond with the different forms of the plugs and valves, are mounted on bars N or N' connected to the disks O P, from one to the other of which they extend, so as to be adjusted radially to shift them for plugs or valves of different sizes, and to shift them to different bevels.

For long tapered plugs A long straight-edged knives D will be fixed on straight bars N', being bolted to the bars by bolts Q passing through slots in them, or in any equivalent way, so that said cutters can be adjusted on said bars at either or both ends, and said cutters may also be pivoted to said bars at the end next to the disk O, if preferred. They may also be used with good results without being adjustably connected to said bars.

The cutters E for the valves, which require to be more oblique to the axis of the centers, and not so long, will be shorter than D, and above or beyond the cutting portion will merge in a bar, N, which will extend to the disk P, said cutters being pivoted to the radially-adjustable sliding blocks S on the disk O.

The bars N', carrying the cutters D, will also be pivoted to these blocks, or the cutters themselves may be, dispensing with the bars N', and having the cutters prolonged so as to connect with disk P. The cutters E may also be affixed to bars N', as cutters D are, if preferred.

The said cutters or their bars are pivoted to the sliding blocks S, for adjusting the cutters radially at one end, and these blocks are so adjusted by sliding the short sleeve T on the spindle or shaft J toward or from the disk, to which sleeve they are connected by the rods U, which are jointed to both so as to impart the required radial movements by such movements of the sleeve. The said sleeve is fastened where required, to hold the blocks when adjusted by the jam-nuts V.

I also propose to have short cutters E without the extensions N, also without the bars N',

for dressing valves only, supported on these radially-sliding blocks only, said cutters being rigidly attached to the said blocks for valves of one particular bevel, or they may be adjusted for different bevels.

The object of this is to avail myself of this mode of supporting and adjusting the cutters in special machines for valves only in which the bars N or N', disk P, and its adjuncts are not required, said devices being only necessary in machines for refitting the plugs, or the same and the valves as the one here shown. For supporting the other ends of the cutters, and adjusting them, I have the disk P screwed on the inner end of the adjusting-screw G, and connected to disk O by three (more or less) bars, W, rigidly attached to disk O, but adjustably attached to disk P, so that it can be shifted toward or from O, the connection being preferably formed by the bars being boxed into the face of the disk, and bolts x passing through longitudinal slots y in the bars; but any other equivalent mode of making the connection may be employed.

The adjustment of the disk is effected when the bolts x are loosened by turning both the disks to screw P forward or back on the screw G till it comes to the right point, and then sliding disk O and shaft J toward or from it, as required. The cutters are adjusted at this end by swinging the bars N N' toward or from the center along the slotted bars Z, and fastening them by bolts, as required.

The cutters D', for dressing out the seats or holes for the plugs A, are mounted on a conical longitudinally and radially grooved stock, A', being confined by disks B', through which oblique extensions C' on their ends project, the slots in the disks being correspondingly formed,

so that by moving the disks toward each other the cutters will be forced outward, and by moving them the other way they will be moved inward.

The said disks are moved in the direction to force the cutters outward by the nuts E', and held in position by them. The resistance of the work on the cutters tends to keep the disks against the nuts and force them outward when the nuts are screwed back; but I may have the nuts swiveled to the disks so as to draw said disks back by the nuts, if preferred.

To obtain the best results in dressing the surfaces to be refitted truly, I use cutters with edges or operating surfaces of different construction or form.

The spindle or shaft J is made in two parts, one of which screws into a socket in the end of the other for shifting the disk O, which it may sometimes be preferred to do it in this way. The parts are made fast by a jam-nut, K'.

Having thus described my invention, I claim as new and desire to secure by Letters Patent—

1. The combination of the spindle J, disk O, sliding blocks S', adjusting-sleeve T, links U, and jam-nuts V, substantially as specified.
2. The combination of disk P and slotted bars W, of the adjustable disk O, as and for for the purpose specified.
3. The combination, with the center C and screw G, of the cutter supporting and adjusting disk P, substantially as specified.

CHARLES F. HALL.
